UNITED STATES PATENT OFFICE.

ISAAC N. THOMAS, OF LIMA, OHIO.

WASHING-MACHINE.

SPECIFICATION forming part of Letters Patent No. 663,371, dated December 4, 1900.

Application filed July 31, 1900. Serial No. 25,452. (No model.)

To all whom it may concern:

Be it known that I, ISAAC N. THOMAS, a citizen of the United States, residing at Lima, in the county of Allen and State of Ohio, have 5 invented new and useful Improvements in Washing-Machines, of which the following is a specification.

In United States Patent No. 652,552, granted to me June 26, 1900, I have shown and described certain improvements in washing-machines in which the washing apparatus is mounted upon a base-board, which base-board rests upon the upper edges of the tub. It has been found that some means should be 15 provided for preventing the displacement of said base-board from the upper edges of the tub, due to the vibration caused by the operation of the pounder, and means whereby the base-board carrying the washing apparatus may be swung up into a vertical position 20 for the purpose of draining the pounders and permitting the introduction of the clothes to be washed into the tub. My present invention has to do with means for supporting the base-board of a washing apparatus upon the tub and for securing the same in place, which will provide for the swinging movement of said base-board to a vertical position without danger of disconnection of the same from the 25 tub.

The invention consists of a fulcrum piece or support secured or adapted to be secured to the sides of the tub and extending inwardly toward the center thereof, the same comprising 30 a horizontally-disposed yoke-shaped member having outwardly-extending lips or projections at the ends of the side branches thereof and a vertically-disposed yoke-shaped member secured to the side branches of the 35 other member and extending upwardly therefrom and a base-board for the washing apparatus having a tenon on one end adapted to be introduced into the space between the members of said fulcrum piece or support 40 and provided on its under side with a plate 45 provided with a flange adapted to engage the lower edge of the horizontal member of said support when said base-board is in its raised or vertical position.

50 The invention also consists in certain features and details of construction and combi-

nations of parts, which will be hereinafter more fully described and claimed.

In the drawings forming part of this specification, Figure 1 is a sectional elevation of 55 an ordinary tub, showing my invention in connection therewith. Fig. 2 is a detail perspective view of the fulcrum-support. Fig. 3 is a perspective view of a portion of the base-board, and Fig. 4 is a similar view showing the base-board in connection with the fulcrum-support.

Like reference-numerals indicate like parts in the different views.

In the drawings I have illustrated my invention in connection with an ordinary tub 1 and reciprocating washing apparatus comprising the pounders 2, the vertically-movable rod or shaft 3, to which said pounders are connected, and the operating-lever 4, connected with said shaft. The shaft 3 extends through the base-board 5, and the latter is provided at one end with a tenon 6, on opposite sides of which are the shoulders 7. Secured to the under side of the base-board 75 5 is a plate 8, having a downwardly-extending flange 9 in line with the end of the tenon 6.

The fulcrum piece or support 10 for the base-board 5 is secured to the inner surface of the side of the tub 1 adjacent to its upper 80 end and extends inwardly toward the center of the tub. The said fulcrum-piece is made up of a yoke-shaped horizontally-disposed member 11, preferably constructed of sheet metal, and having its ends bent outwardly 85 from the branches of the yoke to form the lips or projections 12 12, and of the vertically-disposed yoke-shaped or inverted-U-shaped member 13, whose ends are secured to the side branches of the member 11 and which extends 90 upwardly from said member 11. Within the space between the members 11 and 13 of the support 10 fits the tenon 6 on the end of the base-board 5. When said base-board is in its horizontal position, with the pounders down 95 in the tub 1, one end of said base-board is supported by the horizontal member 11 of the fulcrum-piece 10, while the opposite end thereof rests upon the upper edge of the tub. This end of the base-board is provided with suitable fastening means. In the form of my invention herein shown I employ a hook 14,

pivoted to the base-board 5, adapted to engage a loop or eye 15, secured to the outside of the tub 1. The plate 8 when the washing apparatus is in operative position serves as a 5 wear-plate for the under side of the base-board 5. When said base-board is raised to its vertical position, the same is supported by the engagement of the shoulders 7 with the upper edges of the horizontal member 11 of 10 the fulcrum-piece 10, and outward movement of said base-board is prevented by the engagement of one side thereof with the vertically-disposed member 13 of said fulcrum-piece. Lateral swinging movement of the 15 base-board is prevented by the engagement of the flange 9 on the plate 8 with the lower edge of the horizontal member 11 of the fulcrum-piece. It will thus be seen that the base-board 5, with the washing apparatus connected therewith, may be readily and conveniently moved to or from its operative position on the tub 1 or may be entirely disconnected therefrom by slipping the tenon 6 out of the fulcrum-piece 10. At the same time, by reason of the fact that the fulcrum piece or support 10 is secured to the inner surface of the tub 1, the pounds 2 may be caused to drain back into the tub instead of to the outside thereof. Furthermore, by having the fulcrum piece or support 10 extending toward the center of the tub the washing apparatus when in its raised position is less likely to overbalance the tub and upset the same.

Having now described my invention, what 35 I claim as new, and desire to secure by Letters Patent, is—

1. The combination with a washtub and the base-board of a washing apparatus to be used in connection therewith, the said base-board being provided with a tenon at one end, 40 of a fulcrum piece or support for said base-board secured to the inner side of said tub and comprising a horizontally-disposed, yoke-shaped member provided with securing means 45 at its ends, and an upwardly-extending, vertically-disposed yoke-shaped member secured to said horizontally-disposed member, the tenon on said base-board fitting within the

angular space between the members of said support, as and for the purpose set forth. 50

2. The combination with a washtub and the base-board of a washing apparatus to be used in connection therewith, the said base-board being provided with a tenon at one end, 55 of a fulcrum piece or support for said base-board secured to the inner side of said tub and comprising a horizontally-disposed yoke-shaped member having outwardly-extending lips or projections at the ends of the branches thereof constituting securing means, and 60 an upwardly-extending, vertically-disposed, yoke-shaped member secured to said horizontally-disposed member, the tenon on said base-board fitting within the angular space 65 between the members of said support, and locking means for said board at the end opposite said tenon, as and for the purpose set forth.

3. The combination with a washtub and the base-board of a washing apparatus to be 70 used in connection therewith, the said base-board being provided with a tenon at one end, of a fulcrum piece or support for said base-board secured to the inner side of said tub and comprising a horizontally-disposed, yoke-shaped member provided with securing means 75 at its end, and an upwardly-extending, vertically-disposed, yoke-shaped member secured to said horizontally-disposed member, a plate secured to the under side of said base-board having a flange thereon adjacent to the end of said tenon, the tenon on said base-board fitting within the angular space between the members of said support and the flange on said plate adapted to engage the 80 lower edge of the horizontally-disposed member of said support when said base-board is in its raised position, as and for the purpose set forth.

In testimony whereof I have hereunto set 85 my hand in presence of two subscribing witnesses.

ISAAC N. THOMAS.
